United States Patent Office

Des. 195,672
Patented July 16, 1963

195,672

INFANT'S CHAIR

Earl F. Hamilton and Ralph B. Lay, Columbus, Ind., assignors to Hamilton Cosco, Inc., Columbus, Ind., a corporation of Indiana

Filed Feb. 12, 1962, Ser. No. 68,786

Term of patent 14 years

(Cl. D15—1)

Fig. 3.

FIG. 1 is a perspective view of an infant's chair showing our new design;

FIG. 2 is a side elevation thereof, but showing said chair in its reclining position; and

FIG. 3 is a rear elevation thereof.

We claim:

The ornamental design for an infant's chair, as shown.
